DESIGN FOR A FOLDING CHAIR

Willard H. Bond, Jr., Grand Rapids, Mich., assignor to American Seating Company, Grand Rapids, Mich., a corporation of New Jersey

Application October 21, 1946, Serial No. 134,108

Term of patent 14 years

(Cl. D15—1)

To all whom it may concern:

Be it known that I, Willard H. Bond, Jr., a citizen of the United States, residing at Grand Rapids, in the county of Kent and State of Michigan, have invented a new, original, and ornamental Design for a Folding Chair, of which the following is a specification, reference being had to the accompanying drawing, forming a part thereof.

other leg of the chair, taken on line 4—4 of Figure 2.

I claim:

The ornamental design for a folding chair, substantially as shown.

WILLARD H. BOND, JR.
